US0D1006848S

(12) **United States Design Patent** (10) Patent No.: **US D1,006,848 S**
(45) Date of Patent: ** Dec. 5, 2023

(54) **MOBILE ROBOT BASE WITH MAST AND SHELVES**

(71) Applicant: **Locus Robotics Corp.**, Wilmington, MA (US)

(72) Inventors: **William Richardson Jones**, San Francisco, CA (US); **Colin Alexander Davis**, New Orleans, LA (US); **John Stephen Lanier**, New Orleans, LA (US); **Seth Edwards Allen**, Newton, NH (US); **Michael Sussman**, Winchester, MA (US); **Michael Charles Johnson**, Ashland, MA (US); **Sean Johnson**, Danvers, MA (US); **Brad Edward Fiore**, Vernon, CT (US); **Mark Kniffin**, Brookline, MA (US); **Hian Kai Kwa**, Reading, MA (US); **Christina Nicole Fong**, Somerville, MA (US); **Jonathan David Dix**, Stoneham, MA (US); **Peter Sussman**, Wilmington, MA (US); **John Boezi, III**, Doraville, GA (US)

(73) Assignee: **Locus Robotics Corp.**, Wilmington, MA (US)

(**) Term: **15 Years**

(21) Appl. No.: **29/815,895**

(22) Filed: **Nov. 17, 2021**

(51) LOC (14) Cl. **15-99**

(57) **CLAIM**

We claim the ornamental design for a mobile robot base with mast and shelves, as shown and described.

DESCRIPTION

FIG. 1 is a top, front perspective view of a mobile robot base with mast and shelves showing our new design;

FIG. 2 is a front perspective view thereof;

FIG. 3 is back perspective view thereof;

FIG. 4 is a right side view thereof;

FIG. 5 is a left side view thereof;

FIG. 6 is a top plan view thereof; and,

FIG. 7 is a bottom plan view thereof.

In the drawings, the broken lines represent portions of the article which form no part of the claimed design.

1 Claim, 6 Drawing Sheets
